(57) **CLAIM**

The ornamental design for a beverage container, as shown and described.

DESCRIPTION

FIG. 1 is a perspective view of a beverage container, showing the new design;

FIG. 2 is a side elevational view of the beverage container; FIG. 3 is a top plan view of the beverage container; and, FIG. 4 is a bottom plan view of the beverage container.

The broken line showing of the environment is for illustrative purposes only and forms no part of the claimed design.
